[57] CLAIM

The ornamental design for a tie for load ejector lattices, as shown and described.

DESCRIPTION

FIG. 1 is a perspective view of the tie for load ejector lattices;

FIG. 2 is a front view of FIG. 1;

FIG. 3 is a top view of FIG. 1; and,

FIG. 4 is a rear view of FIG. 1.

The tie for load ejector lattices is shown broken away to indicate indeterminate length.

FIG. 1

FIG. 2

FIG. 3

FIG. 4
